United States Patent [19]

Erickson et al.

[11] Patent Number: Des. 316,739

[45] Date of Patent: ** May 7, 1991

[54] WATER DISTILLING UNIT

[75] Inventors: **Theodore B. Erickson; Ivan F. Reed; Harold D. Johnson**, all of Lincoln, Nebr.

[73] Assignee: **Pure Water, Inc.**, Lincoln, Nebr.

[**] Term: **14 Years**

[21] Appl. No.: **495,845**

[22] Filed: **Mar. 19, 1990**

[52] U.S. Cl. **D23/207**

[58] Field of Search D23/200, 207-209; 202/81-83, 160, 176, 181, 185.3, 185.5, 206, 234, 239; 210/153, 162-163, 172, 190.1, 198.1, 198.3
